UNITED STATES PATENT OFFICE

141,974

DESIGN FOR A SHOE WELT

Wallace C. Wright, Brookfield, N. H., assignor to Wright-Batchelder Corporation, Boston, Mass.,
a corporation of Massachusetts

Application November 15, 1944, Serial No. 116,349

Term of patent 14 years

(Cl. D7—6)

To all whom it may concern:

Be it known that I, Wallace C. Wright, a citizen of the United States and a resident of Brookfield, county of Carroll, and State of New Hampshire, have invented a new, original, and ornamental Design for a Shoe Welt, of which the following is a specification, reference being made to the accompanying drawing, forming part thereof.

In the drawing the figure is a view, in perspective, of a piece of shoe welt, showing my new design.

I claim:

The ornamental design for a shoe welt, as shown.

WALLACE C. WRIGHT.
